UNITED STATES PATENT OFFICE

2,480,701

DOOR ARRESTOR

Abraham Thomas Bradbury, Atlanta, Ga.

Application January 15, 1945, Serial No. 572,889

10 Claims. (Cl. 16—86)

This invention relates generally to door stops or arresters and more particularly to an arrester of the type which prevents doors from latching on being moved to a substantially closed position.

Door stops or arresters of this general type are well known in the art and in some instances take the form of a device looped around the edge of the door and fastened over both knobs, the portion passing around the edge of the door preventing its being fully closed to latching position. While these devices are highly useful in hospitals, etc., in holding doors slightly ajar so that the knob need not be turned when it is desired to fully open the door, they are most unsightly, become badly soiled and are of relatively short life.

It is the chief object of the present invention to provide an improved door arrester which eliminates the above mentioned undesirable characteristics of prior door arresters.

It is another important object of the present invention to provide a door arrester which may be installed in a door, jamb or threshold in the manner of other hardware so as to be visible but inconspicuous when in operative position.

A further object of the invention is to provide a door arrester having operative and inoperative positions so that a door equipped with the same may be arrested adjacent the jamb without latching or permitted to close or latch, respectively, in the usual manner.

Other objects and advantages of the present invention will become apparent during the course of the following description.

In the drawings I have illustrated one embodiment of the present invention. In this showing:

Figure 1 is a perspective view of the invention mounted in operative position in the edge of and above the usual latch of a door which has been swung to a position adjacent the door jamb;

Figure 2 is a horizontal sectional view of the door arrester in operative position on the edge of a door so as to engage the door jamb;

Figure 3 is a horizontal sectional view of the door arrester in inoperative position;

Figure 4 is a vertical sectional view of the door arrester taken on the line 4—4 of Figure 3, and

Figure 5 is a front view of the door arrester mounted in the edge of a door and in inoperative or concealed position.

In its broad aspects, the present invention comprises a cushioning door arrester adapted to

be mounted in the edge of a door, in a jamb, a threshold, etc., and so constructed as to have operative and inoperative positions either of which may be readily achieved by pressure of the hand upon the movable portion of the arrester.

Referring now to the drawings, numeral 10 designates a flat rectangular metallic frame which is mounted by suitable screws flush with the edge surface 12 of a door 14. The door is also rabbeted to form a rectangular opening as at 16 and projecting therein is a rearwardly extending or inturned flange 18 formed integral with the inner edge portions of the frame 10. It will be noted that one side flange 18, as viewed in Figures 2 and 3, is bent inwardly and backwardly as at 20 in order to form a stop for a plate 22 which closes the opening in the frame 10 and is flush therewith.

The plate 22 is provided with integral upper and lower rearwardly extending or inturned flanges 24 and is pivotally mounted in frame 10 by means of a strong steel pin or bolt 26 passing through apertures in the flanges 18 and 24 as seen in Figure 4. The plate 22 is also formed with a pair of rearwardly extending arcuate side flanges 28 which are bent sharply in a reverse direction adjacent their ends to form a pair of buffer retaining flanges 30. It will be noted that one side flange 28 as seen in Figure 3 is formed so as to provide a projecting lip 32 arranged to engage the recessed stop 20 in the frame flange 18 upon counterclockwise rotation of the plate 22 to closed or inoperative position. As shown, the portion of the plate 22 extending from the bolt 26 to the lip end 32 is longer than the portion extending from bolt 26 to the opposite end. This in effect provides within the aperture defined by the frame 10 an off center or eccentric pivot for the plate 22.

As indicated, a resilient buffer member 34 of rubber, cork, or other comparable deformable and shock absorbing material is securely mounted against the rear side of plate 22 by the flanges 30. This arrangement constitutes a pivoted plate and buffer assembly. The buffer 34 may be notched (not shown) or provided with a vertically extending aperture so that the pin 26 may fit therein or pass therethrough without interference. As shown, the buffer 34 is preferably semi-circular in cross-section, although other forms may obviously be used.

A longitudinally extending arcuate notch 36 is provided in the buffer 34 adjacent one of the retaining flanges 30 for cooperation with a light

spring locking member 38 suitably secured to flange 18 as at 40. This spring locking member retains the buffer 34 and its supporting plate 22 in closed or inoperative position by engaging the notch 36 as shown in Figure 3, or in open or operative position by engaging the corner of plate 22 as in Figure 2.

It will be readily apparent that the plate and buffer assembly may be pivoted with respect to frame 10 from its inoperative, retracted position, as shown in Figures 3-5 inclusive, to its operative, extended position (Figure 2) by a light push on the left side of the plate 22 at a spot suitably designated as at 37 (Figure 5). It will be noted that in operative position the lip 32 again functions as a cooperating stop member with respect to an inside edge of the frame 10.

When the door arrester is in its operative position and the door is swung toward a closed position by the usual door check or other means, the buffer 34 will engage the corner 42 of the trim of the door jamb 44 to quietly and resiliently arrest the motion of the door and prevent its latching. Thus it is possible to open the door without turning the knob when both hands are otherwise engaged.

When it is desired to have a door (equipped with the present invention) close and latch in the conventional manner, the door arrester is pivoted in a counterclockwise direction from the position shown in Figures 1 and 2 to the position shown in Figures 3-5 whereupon the plate 22 will again be flush with the edge 12 of the door 14.

It will now be apparent that the present invention is a device of great utility, simple but rugged in structure, and highly effective in operation. Its installation in a door, jamb, etc., permits a door to be arrested just short of latching position or to be normally closed as desired by simple adjustment of the position of the buffer.

It is to be understood that the form of the invention herewith shown and described is to be taken as a preferred example of the same and that various changes in the shape, size and arrangement of parts may be resorted to without departing from the spirit of the invention or the scope of the subjoined claims.

I claim:

1. A door arrester adapted to be mounted in a door for engagement with the door jamb, comprising a frame defining an aperture therein, a plate pivotally connected to said frame and closing said aperture, a buffer mounted on said plate, and means for retaining said buffer in extended or retracted position with respect to said frame, said means comprising a spring element mounted on said frame and alternately engageable with said plate and said buffer respectively.

2. A door arrester adapted to be mounted in a door for engagement with the door jamb, comprising a frame defining an aperture therein, a plate pivotally connected to said frame and closing said aperture, a buffer mounted on said plate, and means for retaining said buffer in extended or retracted position with respect to said frame, said buffer comprising a resilient arcuate cushion including a grooved portion for cooperation with said retaining means.

3. A door arrester adapted to be mounted in a door for engagement with the door jamb, comprising a rigid frame having inturned flanges defining an aperture therein, a plate pivotally connected to said flanges and closing said aperture, and a buffer mounted on said plate, said flanges

including a stop for said plate and said plate including a lip portion for cooperative engagement with said stop to arrest said plate flush with said frame when said buffer is in a retracted position with reference thereto.

4. A door arrester adapted to be mounted in a door for engagement with the door jamb, comprising a frame defining an aperture therein, a plate pivotally connected to said frame and closing said aperture, said plate having inturned flanges, and a buffer mounted on said plate and retained thereon by said flanges, said buffer being movable between retracted and extended positions with respect to said frame.

5. A door arrester adapted to be mounted in a door for engagement with the door jamb, comprising a frame defining an aperture therein, a plate pivotally connected to said frame and closing said aperture, said plate having inturned flanges, a buffer mounted on said plate and retained thereon by said flanges, and means for retaining said buffer in extended or retracted position with respect to said frame.

6. A door arrester adapted to be mounted in a door for engagement with the door jamb, comprising a frame defining an aperture therein, a plate pivotally connected to said frame and closing said aperture, said plate having inturned flanges, a buffer mounted on said plate and retained thereon by said flanges, and means for retaining said buffer in extended or retracted position with respect to said frame, said retaining means comprising a spring element mounted on said frame and engageable with said plate and said buffer respectively.

7. A door arrester adapted to be mounted in a door for engagement with the door jamb, comprising a frame defining an aperture therein, a plate pivotally connected to said frame and closing said aperture, said plate having inturned flanges, a buffer mounted on said plate and retained thereon by said flanges, and means for retaining said buffer in extended or retracted position with respect to said frame, said buffer comprising a resilient arcuate cushion including a grooved portion for cooperation with said retaining means.

8. A door arrester adapted to be mounted in a door for engagement with the door jamb, comprising a frame defining an aperture therein, a plate pivotally connected to said frame and closing said aperture, said plate having opposed flanges on one side, and a buffer mounted on said plate and retained thereon by said flanges, said buffer being movable between extended and retracted positions with respect to said frame, and being concealable within the door, when in retracted position.

9. A door arrester adapted to be mounted in a door for engagement with the door jamb, comprising a frame defining an aperture therein, a plate having an inner face and an outer face pivotally mounted in said frame, said plate being of a size and shape to fit within and close said aperture, a buffer mounted on the inner side of said plate, said plate and buffer comprising an assembly; and yielding means carried by said frame for engaging and holding said plate and buffer assembly alternatively in aperture closing position and buffer extended position.

10. A door arrester adapted to be mounted in a door for engagement with the door jamb, comprising a frame defining an aperture therein, a plate having an inner face and an outer face eccentrically pivoted within the aperture of said

frame, said plate being of a size and shape to close said aperture, and a buffer mounted on one side of said plate; said plate and buffer comprising an assembly; said plate and buffer assembly being adapted to be swung to buffer extended position outwardly of said aperture and to an aperture closing position whereby when in the buffer extended position one side of said plate cooperatively engages with said frame to act as a stop for said assembly.
